United States Patent Office

Des. 206,684
Patented Jan. 10, 1967

206,684

WRIST TELESCOPE

Michael Bevilacqua, 2027 E. Pinehurst,
Glendora, Calif. 91740

Filed Oct. 21, 1965, Ser. No. 87,685

Term of patent 14 years

(Cl. D57—1)

FIG. 1

FIG. 3

FIG. 4

FIG. 5

FIGURE 1 is a perspective view, showing my new design;

FIGURE 2 is a top view thereof;

FIGURE 3 is a side elevational view thereof;

FIGURE 4 is a front elevational view thereof; and

FIGURE 5 is a bottom view thereof.

The side not shown is the same in appearance as the side shown.

I claim:

The ornamental design for a wrist telescope, as shown and described.
